(57) **CLAIM**

The ornamental design for a pedestal and base for a remote control device, as shown and described.

DESCRIPTION

FIG. 1 is a perspective view of a pedestal and base for a remote control device according to a first embodiment of our new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a pedestal and base for a remote control device according to a second embodiment of our new design.

FIG. 8 is a front view thereof.

FIG. 9 is a top view thereof; and,

FIG. 10 is a bottom view thereof, the left side and right side views, respectively, of the second embodiment being identical to the left side and right side views of the first embodiment.

The rear views form no part of the design and are omitted.
